PRIMEX Product Specification Sheet—Verge PR1500. (online pdf)
2 pgs. Nov. 2017. [Retrieved Nov. 27, 2019] https://primex.com/wp-content/uploads/2018/10/PR1500_Spec_Sheet.pdf.*
(Continued)*Primary Examiner* — Marie D. Fast Horse**CLAIM**The ornamental design of a networking enclosure assembly,
as shown and described.**DESCRIPTION**

FIG. 1 is an exploded view of a networking enclosure assembly;

FIG. 2 is a perspective view of the assembly of FIG. 1;
FIG. 3 is a right-side view of the assembly of FIG. 1, the
left-side being a mirror image;FIG. 4 is a top view of the assembly of FIG. 1, the bottom
being a mirror image;FIG. 5 is a front view of the assembly of FIG. 1; and,
FIG. 6 is a rear view of the assembly of FIG. 1.The broken lines in the drawings depict portions of the
networking enclosure assembly that form no part of the
claimed design. Shade lines on various portions of the
networking enclosure assembly are provided to show
contour and do not show surface ornamentation.**1 Claim, 6 Drawing Sheets**# US D894,146 S
